UNITED STATES PATENT OFFICE.

FREDRICK R. WILCOX, OF STAR LIME WORKS, KENTUCKY.

WAGON-TONGUE SUPPORT.

1,234,843.

Specification of Letters Patent.

Patented July 31, 1917.

Application filed February 12, 1917. Serial No. 148,158.

To all whom it may concern:

Be it known that I, FREDRICK R. WILCOX, a citizen of the United States, residing at Star Lime Works, in the county of Lyon 5 and State of Kentucky, have invented a new and useful Wagon-Tongue Support, of which the following is a specification.

The present invention appertains to devices for supporting the tongues of wagons 10 and other vehicles, and aims to provide a novel and improved attachment applicable to vehicle tongues or poles for supporting them above the ground when the vehicle is standing idle, or while the draft animals are 15 being hitched to the vehicle.

It is the object of the invention to provide a device of that character embodying a leg hinged to the tongue to swing downwardly for supporting the tongue and to 20 swing upwardly against the tongue snugly out of the way, the device having novel means for automatically swinging the leg upwardly against the tongue.

It is also the object of the invention to 25 provide a device of the nature indicated which is extremely simple and inexpensive in construction, which can be readily applied to various vehicle tongues, and which will serve its office in a thoroughly desirable 30 and efficient manner.

With the foregoing and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed without 40 departing from the spirit of the invention.

The invention is illustrated in the accompanying drawing, wherein:—

Figure 1 is a side elevation of the device as applied, portions being broken away.

Fig. 2 is a sectional detail taken on the line 2—2 of Fig. 1, on an enlarged scale.

Fig. 3 is a fragmental plan view showing the connection between the spring and link.

In the drawing, there is depicted a portion 50 of an ordinary vehicle tongue 1, it being understood that the present device can be applied to the tongue of any suitable vehicle, for supporting it above the ground when the vehicle is at a standstill.

The attachment embodies a leg 2 constructed of wood or any other suitable ma-

terial and of suitable length to support the tongue the desired distance above the ground, one end of the leg or support 2 being hinged to the tongue 1, preferably 60 near its free end. A suitable hinge 3 is employed, the same having one leaf 4 secured to the lower surface of the tongue and preferably projecting toward the free end of the tongue, the hinge having a second loose leaf 5, which is preferably of channel-shape, as seen in Fig. 2, to receive the butt end of the leg 2. Said leg is secured firmly to the leaf 5 between the flanges thereof, to provide a strong connection between 70 the leg and tongue. When the leg is not in use, it is swung rearwardly and upwardly against the lower surface of the tongue, as seen in dotted lines in Fig. 1, whereby the leg will be out of the way. To support the 75 tongue, the leg is swung downwardly and forwardly to upright position, as seen in full lines in Fig. 1.

Means is employed for automatically raising the leg against the tongue and for holding it thereagainst, and for this purpose a link 6 formed of wire or other suitable material is employed, the same being doubled or of loop-shape with its longitudinal side members 7 extending obliquely or diagonally 80 across the opposite sides of the tongue 1 in rear of the hinge 3. The members 7 are connected at their upper ends by a yoke or cross piece 8 extending across the upper surface of the tongue, and the lower ends 85 of the member 7 have pintles or fingers 9 extending at an angle toward one another and engaged pivotally through the flanges of the leaf 5 and within the leg 2, as seen in Fig. 2. The members 7 are slidable through 90 staples or suitable guides 10 carried by the sides of the tongue 1 in rear of the hinge 3. The yoke 8 is provided with a kink 11 with which one end of a coiled wire retractile spring 12 is engaged, said spring extending 100 rearwardly from the link 6, as seen in Fig. 1, and having its rear end anchored, as at 13, upon the tongue. The link 6 serves to connect the spring 12 with the leg 2, whereby the retractile tension of the spring will 105 pull the link 6 rearwardly, which in turn will swing the leg 2 rearwardly and upwardly. Thus, when the tongue is lifted or the vehicle moved forwardly so as to release the leg 2, the leg will be swung rearwardly 110 and upwardly against the tongue under the influence of the spring 12, and the spring

will hold the leg in place out of the way. This makes the action automatic, and relieves the driver of the necessity of swinging the leg out of the way.

5 A staple 14 or other suitable stop is applied to the upper surface of the tongue 1 at a suitable point, whereby to be engaged by the yoke 8 when the leg 2 is swung to vertical position, thereby limiting the movement of the parts. The members 7 have kinks 15 at suitable points thereof, which move through the staples or guides 10 when the leg 2 is swung against the tongue 1, and said kinks provide shoulders which drop 10 into engagement with the guides 10, thereby serving as a latch for holding the leg 2 against the tongue 1, as seen in dotted lines in Fig. 1. This prevents the jolts or vibrations to which the tongue is subjected, from 15 vibrating or oscillating the leg 2, but said leg can be readily moved downwardly and forwardly by manual force. The spring 12 not only pulls the link 6 rearwardly, but also tends to swing the rear portion thereof 20 downwardly whereby the kinks or shoulders 15 snap into engagement with the guides 10 as above indicated.

Having thus described the invention, what is claimed as new is:

- 30 1. The combination with a vehicle tongue, of a leg hinged thereto for supporting it, a guide carried by the tongue, a link pivotally connected with the leg and slidably through said guide, and a spring carried by 35 the tongue connected to said link for swinging the leg against the tongue.
2. The combination with a vehicle tongue, of a leg hinged thereto for supporting it, a

guide carried by the tongue, a link pivotally connected with the leg and slidably through 40 said guide, and a spring for swinging the leg against the tongue, said link having a portion to snap into engagement with the guide for holding the leg against the tongue.

3. The combination with a vehicle tongue, 45 of a leg hinged thereto to support it, a guide carried by the tongue, a link connected to the leg slidable through said guide and extending obliquely across the tongue, said link having a portion engageable with said 50 guide for holding the leg against the tongue, and a spring connecting said link and tongue for swinging the leg against the tongue and moving said portion into engagement with the guide.

4. The combination with a vehicle tongue, of a leg hinged thereto for supporting it, guides carried by the sides of the tongue, a link having longitudinal side members slidably through said guides and extending obliquely across the sides of the tongue, the lower ends of said members being pivotally engaged with the leg, the link having a yoke connecting the upper ends of said members, said members having portions to snap into 65 engagement with said guides when the leg is swung upwardly against the tongue, and a coiled wire retractile spring connecting said yoke and tongue.

In testimony that I claim the foregoing 70 as my own, I have hereto affixed my signature in the presence of two witnesses.

FREDRICK R. WILCOX.
